 FIG. 3 is a rear view thereof;
 FIG. 4 is a left side view thereof;
 FIG. 5 is a right side view thereof;
 FIG. 6 is a top plan view thereof;
 FIG. 7 is a bottom view thereof;
 FIG. 8 is a cross-sectional end view thereof taken along the line 8-8 in FIG. 2;
 FIG. 9 is a front perspective view of a second embodiment of the stone retrieval basket for medical device showing our new design;
 FIG. 10 is a front view thereof;
 FIG. 11 is a rear view thereof;
 FIG. 12 is a left side view thereof;
 FIG. 13 is a right side view thereof;
 FIG. 14 is a top plan view thereof;
 FIG. 15 is a bottom view thereof;
 FIG. 16 is a cross-sectional end view thereof taken along the line 16-16 in FIG. 10;
 FIG. 17 is a front perspective view of a third embodiment of the stone retrieval basket for medical device showing our new design;
 FIG. 18 is a front view thereof;
 FIG. 19 is a rear view thereof;

FIG. 20 is a left side view thereof;
 FIG. 21 is a right side view thereof;
 FIG. 22 is a top plan view thereof;
 FIG. 23 is a bottom view thereof;
 FIG. 24 is a cross-sectional end view thereof taken along the line 24-24 in FIG. 18;
 FIG. 25 is a front perspective view of a fourth embodiment of the stone retrieval basket for medical device showing our new design;
 FIG. 26 is a front view thereof;
 FIG. 27 is a rear view thereof;
 FIG. 28 is a left side view thereof;
 FIG. 29 is a right side view thereof;
 FIG. 30 is a top plan view thereof;
 FIG. 31 is a bottom view thereof;
 FIG. 32 is a cross-sectional end view thereof taken along the line 32-32 in FIG. 26;
 FIG. 33 is a front perspective view of a fifth embodiment of the stone retrieval basket for medical device showing our new design;
 FIG. 34 is a front view thereof;
 FIG. 35 is a rear view thereof;
 FIG. 36 is a left side view thereof;
 FIG. 37 is a right side view thereof;
 FIG. 38 is a top plan view thereof;
 FIG. 39 is a bottom view thereof;
 FIG. 40 is a cross-sectional end view thereof taken along the line 40-40 in FIG. 34;
 FIG. 41 is a cross-sectional end view thereof taken along the line 41-41 in FIG. 34;
 FIG. 42 is a front perspective view of a sixth embodiment of the stone retrieval basket for medical device showing our new design;
 FIG. 43 is a front view thereof;
 FIG. 44 is a rear view thereof;
 FIG. 45 is a left side view thereof;
 FIG. 46 is a right side view thereof;
 FIG. 47 is a top plan view thereof;
 FIG. 48 is a bottom view thereof;
 FIG. 49 is a cross-sectional end view thereof taken along the line 49-49 in FIG. 43;
 FIG. 50 is a front perspective view of a seventh embodiment of the stone retrieval basket for medical device showing our new design;
 FIG. 51 is a front view thereof, a rearview, a top view, a bottom view being the same image thereof;
 FIG. 52 is a left side view thereof;
